UNITED STATES PATENT OFFICE.

STEPHEN E. BURKE, OF EDON, OHIO, ASSIGNOR TO THE BURKE-BOLL-MEYER MANUFACTURING COMPANY, OF WAUSEON, OHIO.

WINDMILL-OILER.

SPECIFICATION forming part of Letters Patent No. 749,526, dated January 12, 1904.

Application filed January 20, 1903. Serial No. 139,783. (No model.)

To all whom it may concern:

Be it known that I, STEPHEN E. BURKE, a citizen of the United States, residing at Edon, in the county of Williams and State of Ohio, have invented a new and useful Windmill-Oiler, of which the following is a specification.

The invention relates to improvements in devices for lubricating windmills.

The object of the present invention is to improve the construction of devices for supplying the bearings of a windmill with a lubricant and to provide a simple and comparatively inexpensive windmill-oiler designed to be fixed to a windmill at the top thereof and adapted to be readily connected with the various bearings of the same and capable of being operated from the ground to deliver a predetermined quantity of oil to the bearings when desired.

With these and other objects in view the invention consists in the novel combination and arrangement of parts hereinafter fully described, illustrated in the accompanying drawings, and particularly pointed out in the claims hereto appended, it being understood that changes in the form, proportion, and minor details of construction within the scope of the claims may be made without departing from the spirit or sacrificing any of the advantages of the invention.

In the drawings, Figure 1 is a vertical sectional view of a windmill-oiler constructed in accordance with this invention, the vertically-movable plunger or lubricant-carrier being arranged at the bottom of the vertical tube or way. Fig. 2 is a similar view, the vertically-movable plunger or lubricant-carrier being raised for delivering a charge of oil to the distributing pipes or tubes. Fig. 3 is a horizontal sectional view on the line 3 3 of Fig. 1. Fig. 4 is a similar view on the line 4 4 of Fig. 1, illustrating the construction of the stop for limiting the upward movement of the plunger or oil-carrier.

Like numerals of reference designate corresponding parts in all the figures of the drawings.

1 designates an oil can or receptacle having a central vertical tube 2 and provided with

a tapered lower portion or bottom 3 for directing the lubricant toward the lower portion of the vertical tube 2. The vertical tube 2, which extends entirely through the oil-can, projects above and below the same and is constructed of cold drawn steel or other suitable material, and its lower end is closed by a vertical plug 4, constructed of steel or other suitable material and extended beyond the lower end of the tube and secured by a set-screw 5 or other suitable fastening device in an opening 6 of a bracket-arm 7, whereby the lubricator is detachably mounted on a windmill and is adapted to be readily applied to any windmill. The oil can or receptacle, which may be constructed of any suitable material, is preferably cylindrical, and it is provided at its top 8, which is tapered, with a suitable filling-opening having a screw-cap 9 or other suitable closure; but suitable means may be provided, if desired, for supplying the can or receptacle 1 with oil from the base of the tower.

The vertically-disposed centrally-arranged tube 2 forms a guide or way for a vertically-reciprocating plunger or oil-carrier 10, which is adapted to convey a quantity of oil from the can or receptacle to a series of distributing-pipes 11, located above the said oil can or receptacle and arranged at an inclination, as clearly illustrated in Figs. 1 and 2 of the drawings. The vertically-movable plunger or oil-carrier 10 is provided near its lower end with an annular recess 12, forming a reduced portion or stem and providing an oil-chamber, whereby when the plunger or carrier is elevated from the position illustrated in Fig. 1 of the drawings to that illustrated in Fig. 2 a quantity of oil will be conveyed upward to the distributing-pipes and supplied to the bearings of a windmill. The lower portion of the central vertical guide-tube 2 is provided with upper and lower supply-apertures 13 and 14, arranged in pairs, as illustrated in Fig. 1, and lying above and below the lower end of the plunger or carrier in the lowest position to permit oil to flow from the interior of the can or receptacle to the chamber or recess 12 and also to cause the oil in the lower portion of the tube 2 to flow therefrom to the interior of

the can when the plunger or carrier descends, whereby the oil within the lower end of the guide-tube is prevented from interfering with the downward movement of the plunger or carrier. The upper end 15 of the vertical stem or plug 4 is tapered and extends above the openings 14 to prevent the lower end of the plunger or carrier from closing the same.

- 10 The distributing-pipes 11, which are preferably tapered as shown, are mounted upon and suitably secured to the tapered or conical top 8 of the oil can or receptacle, and the inclination of the pipes 11 is sufficient to cause the oil to flow readily through them to the 15 bearings to be lubricated. The outer tapered end of the distributing-pipes project beyond the side walls of the can or receptacle and form nipples 16 for the reception of flexible tubes 17 for connecting the distributing-pipes 20 with the movable elements of a windmill, and where flexible tubing is not required any other form of tube may be employed for conveying the oil to the bearings to be lubricated. Any number of distributing pipes and tubes 25 may be employed, and the flexible tubes are detachably fitted on the tapered projecting nipples of the distributing-pipes. The central vertical guide-tube is provided above the oil can or receptacle with delivery perforations 30 or apertures 18 and 19, arranged in pairs and communicating with the enlarged ends of the distributing-pipes to permit air to pass into the oil chamber or recess 12 and to allow the oil to flow readily therefrom.
- 35 The upper end of the plunger or carrier is reduced to form a shank or lug 20, having a perforation into which is linked one end of the chain 21; but any other form of flexible connection may be employed. The flexible connection extends upward from the plunger and passes over a grooved guide-pulley 22 and extends outward and downward from the upper end of the tube, being connected at its outer end with a wire 23 or other suitable connection for enabling the plunger or carrier to be elevated from the base of the windmill-tower. The wire 23 extends downward through a guide 24; but any other form of connection may be employed. The guide 24 is mounted 40 on the oil can or receptacle at one side thereof, and any number or character of guides may be provided for this purpose. The upper end of the central guide-tube is split longitudinally and cut laterally, the partially-severed portions 25 being bent outward, as clearly shown in Fig. 3 of the drawings, and arranged at opposite sides of the grooved guide-pulley. The upper end of the guide-tube is covered 45 by a hood or cap 26, constructed of sheet metal and tapered, as shown. The inner portion of the hood, which is provided with a horizontal top, conforms to the configuration of the adjacent portions of the tube, and the outer portion, which projects beyond the partially-severed portions of the tube, has an inclined

outer wall. The operating connection is returned to its initial position after a quantity of oil has been delivered to the distributing-pipes by means of a coiled spring 27, secured at its upper end to the hood by a hook 28 and connected at its lower end with the wire by means of a ring or link 29, receiving the lower end of the chain and provided with an arm or projection. The arm or projection is suitably secured to the spring; but any other suitable means may be employed for connecting the spring with the operating means. The spring returns the wire to its initial position, and thereby allows the plunger or carrier to descend to the lower end of the guide-tube. 80

The upward movement of the plunger or carrier is limited by a stop 30, consisting of an approximately U-shaped piece of flexible metal and arranged horizontally a short distance below the cap or hood, as clearly shown in Fig. 2. 85 The guide-tube is provided at opposite sides with slots 31 for the reception of the sides of the stop, which slides horizontally in the slots and which has the terminals 32 of its sides bent at an angle, as indicated in Fig. 1, to 90 form lugs for preventing the withdrawal of the stop. The stop is removable, and the sides project inward into the vertical guide-tube and are arranged in the path of the upper end of the plunger or carrier to limit the upward 95 movement of the same. The stop limits the upward movement of the carrier, so that when the same is raised for lubricating the bearings the recess, which forms the oil-chamber, will register with the upper apertures 18 and 14, 100 which communicate with the distributing-pipes 11.

Any number of apertures may be provided at the upper and lower portions of the guide tube or way for the purposes hereinbefore set forth, and the upper apertures of the lower set are larger than the lower ones, and the lower apertures of the upper set are of a greater diameter than the upper ones; but the construction may be varied from that described. 105

It will be seen that the windmill-lubricator is exceedingly simple and inexpensive in construction, that it is adapted to be readily applied to a windmill, and that it is capable of being operated at will to supply the bearings 115 of a windmill with a predetermined quantity of oil. It will also be apparent that the device is operable from the base of the tower of a windmill and that after an operation the operating means is returned to its initial position to permit the plunger or carrier to descend freely to the bottom of the tube. 120

What I claim is—

1. A device of the class described, comprising a reservoir or receptacle, a vertical tube 125 extending into the reservoir or receptacle and having delivery and supply apertures, distributing-pipes located above the surface of the lubricant and communicating with and extending from the delivery-apertures, and a verti- 130

cally-movable carrier operating in the tube for conveying the lubricant from the supply to the delivery apertures thereof, substantially as described.

5 2. A device of the class described comprising a receptacle or reservoir, an upright guide-tube arranged within the reservoir or receptacle, a series of distributing-pipes extending from the tube and located above the surface 70 of the lubricant, and an oil-carrier operating in the tube for conveying the lubricant to the distributing-pipes, substantially as described.

3. A device of the class described comprising a reservoir or receptacle having a tapering top, a series of inclined distributing-pipes supported by the top of the reservoir or receptacle, and an oil-carrier for conveying the lubricant upward to the upper ends of the distributing-pipes, substantially as described.

5 4. A device of the class described comprising a reservoir or receptacle having a conical top, an oil-tube extending upward through the top of the reservoir or receptacle, a series of inclined distributing-pipes supported by the 80 conical top of the reservoir or receptacle and extending from the said tube, and a carrier operating in the tube for conveying a lubricant to the upper ends of the distributing-pipes, substantially as described.

5 5. A device of the class described comprising a reservoir or receptacle, inclined distributing-pipes located above the surface of the lubricant, and a carrier operable in the receptacle or reservoir for conveying the lubricant upward to the upper ends of the distributing-pipes, substantially as described.

6. A device of the class described comprising a reservoir or receptacle, a tube extending through the same, a plug secured within 10 the lower end of the tube and projecting therefrom, a bracket-arm receiving the plug and provided with means for engaging the same, distributing-pipes extending from the tube at a point above the surface of the lubricant, and a carrier operating in the tube for conveying the lubricant to the distributing-pipes, substantially as described.

7. A device of the class described comprising a reservoir or receptacle, a tube extended 15 through the bottom of the same and provided

at its lower portion with upper and lower supply-apertures located within the reservoir or receptacle, a plug provided with a tapered upper end and secured within the lower end 55 of the tube, the tapered end projecting above the lower aperture, a plunger or carrier operating in the tube and provided at its lower portion with a recess adapted to register with the upper supply-aperture, and means for 60 conveying a lubricant from the carrier when the same is elevated to the bearings to be lubricated, substantially as described.

8. A device of the class described comprising a reservoir or receptacle, a tube extended 65 through the bottom of the same and provided

at its lower portion with upper and lower supply-apertures located within the reservoir or receptacle, a plug provided with a tapered upper end and secured within the lower end of the tube, the tapered end projecting above 70 the lower aperture, a lubricant-carrier operating in the tube and means for conveying a lubricant from the carrier when the same is elevated, substantially as described.

9. A device of the class described comprising a reservoir or receptacle, a tube connected therewith and provided with upper and lower supply-apertures communicating with the lower part of the same, a carrier operating in the tube and provided at its lower portion with 80 a recess forming an oil-chamber, means located within the tube for supporting the carrier above the lower aperture and with the upper aperture in communication with the recess and means for conveying a lubricant from the carrier when the same is elevated.

10. A device of the class described, comprising a reservoir or receptacle, an upright tube communicating therewith, a lubricant-carrier operating in the tube, and an inclined distributing-pipe communicating with the tube and supported by the reservoir or receptacle and projecting beyond the same and forming a nipple to receive a flexible tube, substantially 90 as described.

95 11. A device of the class described comprising a reservoir or receptacle, a tube located within the reservoir or receptacle and extending above the same, a distributing-pipe located above the surface of the lubricant, a carrier operating in the tube for conveying a lubricant to the distributing-pipe, and a stop mounted on the tube and located above the reservoir or receptacle and arranged in the path 100 of the carrier for limiting the movement of the same, substantially as described.

12. A device of the class described comprising a reservoir or receptacle, a tube communicating therewith, a carrier operating in the tube, a distributing-pipe located above the 110 surface of the lubricant and extending from the tube, and a stop projecting into the tube above the distributing-pipe, and removable from the exterior thereof, substantially as described.

115 13. A device of the class described, comprising a reservoir or receptacle, a tube communicating therewith and provided with opposite slots, a stop straddling the tube and extending through the slots into the same and provided with means for securing it in position, a carrier operating in the tube and arranged to have its upward movement limited by the stop and means for conveying a lubricant from the carrier when the same is elevated, substantially as described.

120 14. A device of the class described comprising a reservoir or receptacle, a tube communicating therewith and provided with opposite slots, a lubricant-carrier operating in the 125 tube

tube, a stop provided with opposite sides arranged in the slots and having their terminals bent to form lugs for engaging the tube, and a distributing-pipe extending from the tube 5 and arranged to convey a lubricant from the carrier when the same is elevated, substantially as described.

15. A device of the class described comprising a reservoir or receptacle, a tube located 10 within and extending above the same, a lubricant-carrier operating in the tube, distributing-pipes extending from the tube and located above the surface of the lubricant in the reservoir or receptacle, guiding means arranged 15 above the distributing-pipes, and operating mechanism having a flexible connection supported by the guiding means and connected with the carrier, substantially as described.

16. A device of the class described comprising 20 a reservoir or receptacle, a tube located within and extending above the same and provided with a hood, a lubricant-carrier operating in the tube, means for conveying a lubricant from the tube, a guide located within the 25 hood, operating means having a flexible con-

nexion running over the guide and connected with the carrier, and a spring supported by the hood and connected with the operating means, substantially as described.

17. A device of the class described comprising 30 a reservoir or receptacle, a tube located within and extending above the same and having its upper portion split longitudinally and cut laterally, the partially-severed portions being extended beyond the tube, a hood arranged on and connected with the upper split portion of the tube, a guide housed within the hood, a lubricant-carrier arranged within the tube, a flexible connection running over the guide and connected with the carrier, and 35 means for conveying a lubricant from the tube above the level of the same in the reservoir, substantially as described.

In testimony that I claim the foregoing as my own I have hereto affixed my signature in 40 the presence of two witnesses.

STEPHEN E. BURKE.
